UNITED STATES PATENT OFFICE.

FRANK B. DAVIDSON, OF MARSEILLES, ILLINOIS, ASSIGNOR TO HOWE AND DAVIDSON COMPANY, OF EAST ORANGE, NEW JERSEY, A CORPORATION OF NEW JERSEY.

PAPER-ROLL ADJUSTMENT.

No. 823,848.

Specification of Letters Patent.

Patented June 19, 1906.

Application filed July 17, 1905. Serial No. 270,088.

To all whom it may concern:

Be it known that I, FRANK B. DAVIDSON, a citizen of the United States, residing at Marseilles, in the county of LaSalle and State of Illinois, have invented certain new and useful Improvements in Paper-Roll Adjustments; and I do hereby declare that the following is a full, clear, and exact description thereof, reference being had to the accompanying drawings, and to the letters of reference marked thereon, which form a part of this specification.

This invention relates to a novel device for supporting a roll of paper, paper-board, or the like in position to feed the material to a machine in which the material is treated or operated upon in such manner that the roll may be readily shifted laterally with respect to the path of the sheet or web of material as it enters the machine for the purpose of maintaining said web or sheet as it is unwound from the roll in proper alinement with the feed-rolls at the receiving end of the machine.

My improved device is more particularly applicable for holding in position a roll of heavy paper-board, from which such articles as cartons are made, in position to be fed to a coating-machine, by which the material is coated to render the same waterproof, or a cutting-machine, by which blanks of proper dimensions are severed from the web preparatory to scoring the same.

Among the objects of my invention are to provide a simple and readily-operable device of this character whereby the roll-support may be accurately adjusted to a machine, so as to maintain the entering web as it is unwound from the roll in proper alinement with the feed-rolls of the machine, to provide a device which is capable of slight lateral adjustments, and a device which locks the roll-support in place after its adjustment.

The invention consists in the matters hereinafter set forth, and more particularly pointed out in the appended claims.

In the drawings, Figure 1 is a side elevation of a roll supporting and registering device made in accordance with my invention and showing also the receiving end of the machine to which the web is fed. Fig. 2 is a top

plan view of said devices, showing in dotted lines the position of a roll thereon. Fig. 3 is a partial longitudinal section of the device, taken on line 3 3 of Fig. 2. Fig. 4 is a cross-section, with parts broken, taken on line 4 4 of Fig. 2.

As shown in the drawings, A designates as a whole the feed end of a machine, as a coating or cutting machine, in which the web of the strawboard or like material fed from the roll B is operated.

A' A' designate feed-rolls by which the web is fed into the machine, and a a guide-roll located in position to bring the web in horizontal alinement with the coating faces of said feed-rolls.

C designates a base or support located in rear of the machine A and disposed transversely to the path of the web to said machine. D designates, as a whole, a carriage supported on said base and movable longitudinally of the base, and therefore transversely to the path of the web as it is fed into said machine. E E designate standards which rise from said carriage and support at their upper ends said roll B. Said base is provided with suitable tracks or ways on which said carriage is supported and moves. As herein shown, the base comprises an elongated open frame embracing longitudinal side members c and end members c'. The longitudinal members c thereof are provided on their inner faces with inwardly-opening channeled tracks C', which receive lugs d, projecting laterally from the longitudinal side members d' of the carriage. Preferably said lugs are provided with rollers d', which enter said channeled tracks C'. It will be observed that the end member c' at one end of the base is located below the channeled tracks C' in said frame to permit the carriage to be removed entirely from the base.

The standards E are herein shown as bolted at their lower ends to vertical flanges d² d⁴, rising from the end members d⁵ of the carriage. Said standards are provided at their upper ends with upwardly-opening recesses which receive bearing-blocks E', having upwardly-opening bearing-sockets that receive trunnions b, formed on the projecting ends of the core B', about which the web is rolled or wound. Said standards E are pro-

vided at their upper ends with horizontal rearwardly-directed arms E^2 E^2 , which constitute ways or supports over which the projecting trunnions b of the core B' pass as the roll B is approaching the bearings at the upper ends of the standards E when said roll is being placed in position on said standards. Said horizontal arms E^2 E^2 are provided at their outer ends with vertically-swinging hand-levers E^3 , which normally hang downwardly, as shown in Fig. 1. Said hand-levers E^3 are provided for the purpose of assisting to raise the roll B to the level of the arms E^2 when the roll is being placed upon the standards. In practice the roll B is delivered to the carriage over a suitable inclined approach, (not shown,) and the hand-levers engage the ends of the trunnions b when the roll B has been raised sufficiently high and are thereafter swung outwardly and upwardly to assist in raising the roll to bring the trunnions b to the level of the upper faces of said arms E^2 , as before stated. The means for moving said carriage longitudinally of its base or support consists in this instance of a rotative screw-threaded shaft F , having right and left screw-threads at the opposite sides of its longitudinal center. One end of said rotative screw-shaft engages a nut G , that is fixed by bolts or other suitable means in a slot or opening d^4 in the flange d^4 , before referred to, Figs. 3 and 4. The other end of said rotative screw-threaded shaft has screw-threaded engagement with a nut H , which is attached, by means of bolts, to the upper face of the adjacent end member c' of the base. Said shaft is rotated by means of a hand-wheel F' , located intermediate the right and left hand screw-threaded portions of the shaft. With this construction rotation of the shaft by said hand-wheel moves the carriage lengthwise of its base, the direction of movement depending upon the direction of movement of the shaft. By reason of the right and left handed screw-threaded arrangement of the shaft the endwise movement of the carriage is accelerated beyond that which would be imparted by a shaft having a single screw-thread. Moreover, the construction described permits the carriage to be moved practically to the end member of the base or support without the necessity of placing the hand-wheel outside of said end member. It will be observed that the arrangement of the screw-threaded adjusting-shaft is such that the carriage is positively locked in an adjusted position by the same means which is operated to shift the same.

The construction described permits the roll B to be readily placed in position on the carriage and to be rapidly shifted endwise with but little manual exertion to register the web with the feed-rolls of the machine A as it is unwound from its roll. In this manner accurate registration of the web to the

feed-rolls of the machine is assured, notwithstanding that the web is being unwound off of an irregularly-wound roll.

I claim as my invention—

1. A device for supporting a roll of paper and the like in position to feed the same to a machine comprising a stationary base provided with two longitudinal guide members and transverse connecting members joining the same, a carriage supported upon the guide members of said base and movable thereon in a direction transverse to the direction of feeding movement of the paper, standards rising from the ends of the carriage and provided with bearings designed to receive the projecting ends of the core about which the roll revolves, and adjusting means engaged with the base and the carriage for moving said carriage on the base and locking it in its adjusted position. 85

2. A device for supporting a roll of paper and the like in position to feed the same to a machine, comprising a stationary base provided with two longitudinal guide members and transverse connecting members joining the same, a carriage supported upon the guide members of said base and movable thereon in a direction transverse to the direction of feeding movement of the paper, and standards rising from the ends of the carriage and provided with bearings designed to receive the projecting ends of the core about which the roll revolves, said standards being provided with rearwardly-directed horizontal arms constituting ways 100 or supports for the projecting ends of the core. 95

3. A device for supporting a roll of paper and the like in position to feed the same to a machine, comprising a stationary base, a carriage supported upon said base and movable thereon in a direction transverse to the direction of feeding movement of the paper, standards rising from the ends of the carriage and provided with bearings designed 110 to receive the projecting ends of the core about which the roll revolves, rearwardly-directed supporting-arms on said standard, and vertically-swinging hand-levers pivoted to the ends of said supporting-arms. 115

4. A device for supporting a roll of paper and the like in position to feed the same to a machine, comprising a stationary base, a carriage supported upon said base and movable thereon in a direction transverse to the direction of the feeding movement of the paper, said carriage being provided with bearings to receive the ends of the core about which the roll revolves, and means for moving said carriage on its base, comprising a shaft having right and left hand screw-threads, one end of which has screw-threaded engagement with the base and the other end with the carriage and means for rotating said shaft. 120

5. A device for supporting a roll of paper 130

and the like in position to feed the same to a machine, comprising a base consisting of longitudinal side and transverse end members and disposed transversely to the direction of feeding movement of the paper, tracks or ways on the side members of said base, a carriage provided with rollers which rest and roll on said tracks, whereby it is movable longitudinally of said base, said carriage being provided with bearings to receive the ends of the core about which the roll revolves, and means for moving the carriage endwise of said base, comprising a rotative shaft having right and left hand screw-threads, one end of which has screw-threaded engagement with the base, and the other end with the carriage, and a hand-wheel fixed to the shaft between the two sets of screw-threads thereof.

20 6. A device for supporting a roll of paper and the like in position to feed the same to a machine, comprising a base, including longi-

tudinal side members extending transversely to the direction of feeding movement of the paper and provided on their inner faces with 25 inwardly-opening channels, a carriage provided with laterally-extending rollers which travel in said channels, whereby the carriage is movable longitudinally of said base, said carriage being provided with upwardly-opening bearing-sockets adapted to receive the extensions of the core about which the roll revolves, and means for moving said carriage longitudinally of its base and locking it in an adjusted position.

In testimony that I claim the foregoing as my invention I affix my signature, in presence of two witnesses, this 10th day of July,

A. D. 1905.

FRANK B. DAVIDSON.
